UNITED STATES PATENT OFFICE.

SAMUEL FISKE, OF NEW YORK, N. Y.

CANE-SHREDDER.

SPECIFICATION forming part of Letters Patent No. 390,580, dated October 2, 1888.

Application filed May 2, 1887. Serial No. 236,807. (No model.)

To all whom it may concern:

Be it known that I, SAMUEL FISKE, of New York, county of New York, and State of New York, have invented certain new and useful 5 Improvements in Cane-Shredders, of which the following is a full, clear, and exact description, reference being had to the accompanying drawings, and to the letters of reference marked thereon.

10 This invention is designed as an improvement on the apparatus for treating sugar-cane, patented in the United States June 30, 1885, No. 321,006, and its object is to simplify and improve the construction of the cane-shredder and to render it more efficient in action.

Reference is to be had to the accompanying drawings, forming part of this specification, in which similar letters of reference indicate corresponding parts in all the figures.

20 Figure 1 is a side elevation showing the cane-shredder, a set of rolls, cane-carrier, and conducting chutes in their proper relative positions for operating on sugar-cane, the shredder and chutes having parts broken away or 25 removed to exhibit other parts. Fig. 2 is an enlarged end elevation of an end housing of the shredder. Fig. 3 is a plan of a section of shredder back plate, showing doortherein. Fig. 4 is a plan of a cap of a journal-box for shafts 30 of shredder-rolls.

The rolls are set parallel with each other and so that their rings or disks interlock, as indicated, and when in operation they revolve at different speeds and in opposite directions, 35 so that the teeth make a peculiar shearing cut, which prevents them from becoming clogged and causes them not only to cut, but to tear apart into fine fibers or shreds the cane or other fibrous material operated upon, so as to 40 expose the juice-containing cells more completely to the subsequent action of the juice-extractor.

My especial improvements will be hereinafter set forth.

45 In some cases the shredder shafts or drums have been journaled on a horizontal bed-plate and in the same horizontal plane, and in other instances in like boxes set at an angle of about forty-five degrees; but in neither method of 50 construction are the boxes sufficiently rigid to properly withstand the strain when the shredder becomes accidentally crowded with cane.

To remedy this defect, I construct the housings C, as shown, much broader than the diameter of a shredder-roll, with broad bases, by 55 which they may be most rigidly secured to the supporting timbers D, as shown in Fig. 1. A strong back plate, C', secured by bolts a to the flanged upper edges of the housings, adds rigidity to them. In this back plate, C', is a door, 60 E, which may be opened at will to enable the operator to inspect and adjust the disks or remove any material with which the rolls may have become clogged.

As best shown in Fig. 2, it will be seen that 65 the housings have central longitudinal grooves or guides, d, formed at angles of about forty-five degrees to the housing-base, and the sides of these grooves are formed by strong guiding-ribs d', and in the lower ends of these grooves 70 are fashioned the bearings f for the lower roll-shaft. The caps f' of these lower journal boxes or bearings have slotted ends, as shown in Fig. 4, that they may engage on the ribs d' and be easily raised out of the way or entirely removed whenever it may be desired. 75

Both halves of the bearing or boxes g of the upper roll or shaft also have slotted ends, like the cap f', and for the same reasons, so it will be seen that all obstructions can be removed 80 from the grooves d, to the end that both rolls may readily be removed from the shredder for repairs, &c., without displacing anything but the said bearings and a section, h', of the shrouding h, which covers the tops of said 85 grooves and extends from one housing to the other to hold them more firmly in place.

Two check-pieces, h, support a check-block, k', up through which is passed a screw, k'', whose point engages against a boss, l', on the 90 under side of the lower half of the journal-box l, so that by turning the said screw k'' in one or the other direction, as the case may be, the said bearing l, and consequently the upper roll supported therein, may be adjusted nearer to 95 or farther from the lower shredder-roll, in order to shred cane finer or coarser, as may be desired.

A screw, m, passed down through the shrouding h over each housing, bears on a cap, n, 100 fixed on the top of a strong spiral spring, n', whose lower end is engaged in a recessed boss, l'', on the top of the cap of the journal-box l. By this screw the tension of the spring n' may

be regulated or adjusted, and it is designed to so adjust it that it will yield when desirable sufficiently for the upper shredder-roll to lift in order to relieve the shredder, so that pieces 5 of iron or other foreign substances accidentally entering with the cane may pass through without injury to the machine.

These improvements greatly simplify the construction of the shredder, strengthen the 10 weaker parts, diminish the chances of injury to it, remove all difficulties in its operation, and facilitate inspection and repairs, and consequently add much to the commercial value of the machine.

15 In the drawings, F, Fig. 1, represents an ordinary set of juice-expressing rolls; G, a chute for conducting shredded cane from shredder to rolls, and H a chute conducting cane from cane-carrier I to shredder; and K is 20 a frame supporting shredder, cane-carrier, &c.

I am aware of the United States Patents Nos. 59,514, 291,425, and 316,768, and do not claim the constructions therein shown; but,

Having thus described my invention, I desire to secure by Letters Patent—

25 In a cane-shredder, the combination, with the supporting-frame and the shredder-rolls, of housings constructed and arranged substantially as herein shown and described, with broad horizontal bases, central longitudinal 30 grooves or guides, d, formed at angles of about forty-five degrees to said bases, guiding-ribs d', fixed lower shaft-bearings, f, slotted ended lower journal-box caps, f', slotted ended upper journal-boxes, g, shrouding h, removable 35 shrouding-sections h', check-pieces and blocks k k, respectively, adjusting-screws k' m, spring-caps n, and spiral tension-springs n', all adapted to be operated as set forth.

In testimony that I claim the foregoing I 40 have hereunto set my hand, in the presence of two witnesses, this 15th day of April, 1887.

SAMUEL FISKE.
